United States Patent

Des. 241,390
Patented Sept. 14, 1976

241,390

MIRROR SUPPORT

Benny C. Moon, 3135 Spalding Drive,
Atlanta, Ga. 30338

Filed Mar. 14, 1975, Ser. No. 558,438

Term of patent 14 years

Int. Cl. D6—99

U.S. Cl. D6—85

FIG 1

FIG 3FIG 4*FIG 5

FIG. 1 is a perspective view of a mirror support showing my new design;

FIG. 2 is a top plan view thereof;

FIG. 3 is a side elevational view thereof, the side opposite being substantially a mirror image;

FIG. 4 is a rear elevational view thereof; and

FIG. 5 is a front elevational view thereof.

I claim:

The ornamental design for a mirror support, substantially as shown and described.
